UNITED STATES PATENT OFFICE.

FRANK A. CIGOL, OF PATERSON, NEW JERSEY.

DESIGN FOR A TOY BALL.

Application filed January 12, 1927. Serial No. 20,335. Term of patent 14 years.

To all whom it may concern:

Be it known that I, FRANK A. CIGOL, a citizen of the United States, residing at Paterson, in the county of Passaic and State of New Jersey, have invented a new, original, and ornamental Design for a Toy Ball, of which the following is a specification, reference being had to the accompanying drawing, forming a part thereof.

The drawing shows in Fig. 1, a plan, and in Fig. 2 a side elevation of a toy ball embodying my new design.

The surface of the ball is divided into four zones by three sets of substantially equally spaced circumferential ribs, the two polar

zones being occupied by groups of nubs thereon and the other two zones each having four semi-circular groups of nubs the bases or diameters of which groups are, in each zone, coincident with that one of the adjoining bands which adjoins the relatively nearer pole, and there being a single nub in each of the spaces between the said semi-circular groups in each of such other two zones.

I claim:

The ornamental design for a toy ball, as shown and described.

In testimony whereof I affix my signature.

FRANK A. CIGOL.
